UNITED STATES PATENT OFFICE.

ROBERT ELWOOD ELLIS, OF SEATTLE, WASHINGTON, ASSIGNOR TO EDGAR AMES, OF SEATTLE, WASHINGTON.

SCOW.

Application filed December 18, 1924. Serial No. 756,636.

My invention relates to a scow, barge or like vessel constructed of channel shapes and the method of constructing the same.

The particular type of a ship known as a scow is several times broader for its length than the regular ship, and is characterized by being very broad in comparison to its length and depth. The scow is characterized by a blunt bow and stern; in fact, the usual scow is of rectangular form as respects its plan section. The particular type of ship known as a scow involves construction conditions that are not present in regular ship design, approximating a broad platform structure. Such a structure is peculiarly subject to great strains due to its extreme shallowness in comparison to its length and breadth, and also due to the lack of uniformity in disposition of the load. In loading a ship, great care is taken to load the same uniformly, so that the weight is balanced and the vessel is kept in trim, thereby placing no undue strains upon the hull. The exact opposite condition obtains for a scow. A scow may be placed under a chute for loading, and one side or end may be heavily loaded, with the result that the vessel may be disposed at a big angle to the surface of the water, or she may trim by bow or stern,—all of which produces abnormal strains on the structure. A further complicating factor is that the structure must sustain the towing strains while supporting the load,—a condition which, of course, is not ordinary in the case of a ship.

Obviously, due to the square ends of the scow construction, the weight per lineal foot in a fore and aft direction is many times greater at the end portions than amidship. This continuous bearing down of the ends results in causing the scow to buckle upwardly, or "hog", as is known in the art. This means that the bottom is normally under compression, while the deck or top of the scow is under tension. These various conditions make it a requisite and fundamental condition of scow construction that the same be particularly stiff laterally as well as longitudinally and the two should be co-operative, while in ordinary ship con-

struction it is the longitudinal stiffness that must be carefully provided. Since the scow is of square contour, considering a plan view of the structure, the scow must be constructed to resist racking, i. e., having members to resist twisting along the longitudinal axis of the vessel. These requisite conditions create problems peculiar to scow construction. A primary object of my invention is to provide a scow constructed of standard channel shapes, whether structural or ship channels, which satisfies all these requirements.

Another condition which obtains in scow construction is that the same must be capable of economical construction. While scows are subject to rough usage, particularly as respects their loading, nevertheless such type of vessel must be of the most economical construction. A primary object of my invention is to provide a scow characterized by its cheapness of construction.

In ordinary and usual construction, the transverse framing of a scow must be disposed at intervals of about twenty-one inches, and this transverse framing must be supplemented by longitudinal stiffening in the form of keelsons and stringers. A primary object of my invention is to provide a scow which affords the same strength without the employment of many keelsons or stringers, and to provide a scow in which the transverse frame members are spaced a plurality of times greater distance apart as compared with the customary construction. A further requisite condition of a scow is that it must be of shallow draft, i. e., it must be light in weight, so as to operate close to shore lines and in shallow rivers. A primary object of my invention is to provide a scow characterized by its lightness in weight and yet affording the required degree of strength.

Furthermore, there are riveting machines operated by compressed air or hydraulic power known to the trade as "bull riveting devices", which are capable of driving as many as twenty-five hundred rivets per crew in eight hours as against some two hundred rivets per crew in the same time, as at pres-

ent driven by the pneumatic riveting guns. A primary object of my invention is to provide a method of scow construction employing channel shapes, which will make said 5 bull riveting machine applicable to driving some ninety-five percent of the rivets in the scow embodying my invention, whereas at the present time said machine is only applicable to driving some five percent of the 10 rivets in a scow. Manifestly, the employment of rivets throughout the vessel as indicated is in sharp contrast with the employment of machine bolts, where the registering or fairness of the hole must be brought 15 to a fine degree of exactness. In the case of riveting, the said riveting machine makes the rivet metal fill the hole completely, whether or not the same are in exact alignment, so that riveting is stronger as less play 20 is permitted and much more economical as contrasted with the hand-placed machine bolts, and, furthermore, there is no advantage in using machine bolts, in that they are not removable any more readily than are the 25 rivets, since they become heavily corroded after having been in position for a short period.

Another primary object of my invention is the providing of a scow construction, 30 which is indifferent to discrepancies in the width of the channel shapes, by providing a scow design in which no two channel shapes are caused to abut.

In providing for economical construction, 35 I provide for a method of panel construction, which panels are of a length to run from one transverse frame member to another transverse frame. This is in sharp contrast to the practice heretofore employed 40 where the channel members or even plating are always disposed with broken joints,—great pains being taken not to end any adjoining channels or plates along the same transverse line. A primary object of my 45 invention is to provide a steel scow or like vessel constructed of panels formed of channel shapes, which panels extend from one transverse frame member to another transverse frame member, i. e., having said channels in a given panel terminate on a transverse line of the vessel,—the fore and aft 50 length of said panels being determined by the length of the vessel.

A further object of my invention is to 55 provide a scow constructed of panels formed of channel shapes, the bottom panels and the side panels being connected together by longitudinally disposed angle members extending from stem to stern, and the top of 60 the side panels being connected to the deck by means of a continuous angle member.

A further condition which must be provided for in a scow formed of channel shapes is the question of drainage of bilge water.

Manifestly, where the channels extend continuously from stem to stern of the vessel, 65 there will always be the depth of the flange of bilge water present. This is highly objectionable both by reason of the loss in the carrying capacity by reason of this dead 70 weight due to the water, and also said water has a corroding effect and thereby constitutes a positive menace. A primary object 75 of my invention is to provide a scow which is formed of channel shapes, and yet overcomes this drainage difficulty, at the same time affording an economical method of construction.

When channel shapes are ordered cut at the mill to a particular length, there is 80 always considerable discrepancy. They may be more or less than the specified length. Obviously, such expense may be saved if the scow construction is such that such discrepancy may be rendered immaterial, so that the delay and labor cost of cutting to exact 85 fits is obviated. A primary object of my invention is to provide a scow of such construction that the channel shapes may be ordered cut in the mill and assembled in the scow 90 without any correction as to length.

A further condition to be satisfied in a scow made of channel shapes is that the channels be so disposed as to be readily replaceable in case of an accident to the hull, 95 such as the puncturing of any of the channel members, and it is a primary object of my invention to provide a scow formed of panels,—those panels on the bottom being 100 interchangeable inter se and those panels on the sides being interchangeable inter se.

The above mentioned general objects of my invention, together with others inherent in the same, are attained by the device illustrated in the following drawings, the same 105 being merely preferred exemplary forms of embodiment of my invention, throughout which drawings like reference numerals indicate like parts:

Figure 1 is a side view in elevation of a 110 scow embodying the preferred form of my invention;

Fig. 2 is a longitudinal view in section of the same;

Fig. 3 is a fragmentary plan view of the 115 deck of the same;

Fig. 4 is a fragmentary plan view of the bottom of the same;

Fig. 5 is a fragmentary view in transverse section of the same;

Fig. 6 is a view in section, showing the connection of one panel to another panel in the bottom at the transverse frame member;

Fig. 7 is a view in section, showing the connection of one panel to another panel in the hull bottom and the lattice girder connection where the transverse frame member also forms a bulkhead;

Fig. 8 is a detailed view of the deck in transverse section, showing wood filling for the deck channel members;

Fig. 9 is a view of a modified form of bilge plate;

Fig. 10 is a further modified form of the bilge plate connection;

Fig. 11 is a further modified form of bilge connection, where the side channel members 10 extend horizontally;

Fig. 12 is a fragmentary plan view of the bottom of a modified form of a scow embodying my invention; and

Fig. 13 is a detailed view of metal collars 15 to make the bulkhead water-tight in said modified form shown in Fig. 12.

A bulkhead 12 is formed by riveting a boundary bar 13 to a connection plate 14. To the said boundary bar 13, a vertically disposed plate 15 is riveted. The lower member 16 of a longitudinal frame member is secured to said bulkhead. Said securing may be accomplished as herein illustrated by means of an angle clip 17 on one side and 25 by a bulkhead angle stiffener 18 on the opposite side. Thus, said longitudinal frame members may be intercostal. There may be one or more of these longitudinal frame members, the number of which would be 30 decided by the beam and length of the ship. Herein there are illustrated three such longitudinal frame members—one axially disposed and one on each side thereof.

Channel shapes 19 are secured to the connection plate 14 by means of rivets 20, and said channel shapes are secured inter se along their flanges by means of rivets 21. The connection plate 14 is preferably of a width to allow said channel shapes 19 to be positioned in spaced relation to the boundary bar 13. This construction provides for any discrepancy in the lengths of the said channel shapes. It is to be understood that the channel shapes can be placed in the vessel as received from the rolling mill, from which mill they have been ordered cut for certain lengths. However, there will be discrepancies in the length, and these discrepancies are thus provided for by the connection 45 plate 14.

Between the transverse frame members 12 which may be bulkheads, that is, transverse frame members which form a compartment, if the particular use of the scow may so 55 require, may be disposed intermediate transverse members 22. To form a compartment the vertically disposed plate 15 (Fig. 7) would extend to the deck. Herein the term "bulkhead" and "transverse frame member" 60 are used interchangeably and refer to those transverse members mounted at the end or between the ends of the panels. The particular context indicating whether said member is of the compartment type or merely trans- 65 verse channel bracing type; while the term

"intermediate transverse frame member" is restricted to those transverse members resting on the top of the flanges intermediate the length of the panels. These transverse and intermediate transverse members are of 70 truss construction. The intermediate transverse frames may be formed of a channel shape 23 secured on top of the flanges of the bottom channel shapes 19 by means of a plurality of angle clips 24. These intermediate 75 transverse frame members are widely spaced; in fact, are spaced a plurality of times further apart than is customary in transversely framed vessels of similar type.

At the intermediate transverse frames, an 80 angle 25 is disposed in the side having one flange riveted between the flanges of two of the vertically disposed channel shapes. To this angle 25 the deck beam 26 is secured at the ends next to the sides of the vessel by 85 bracket 27. The said beams are also attached to the longitudinal frame members.

The upper member 28 (Fig. 5) of the longitudinal frame member is secured to the upper member of the transverse frame or bulkhead at each of its ends. The lattice members 29 are riveted to bracket plates 37 and 30 at top and bottom. On the deck beams 26 are disposed the channel shapes 31 forming the deck. The upper edge of the 95 upper member 28 of the longitudinal frame is preferably secured between the flanges of two adjacent channel shapes.

In the modified forms shown in Figs. 9 and 10, the bottom and sides of the scow may 100 be in spaced relation and may be secured by a curved or straight bilge plate 32 or 33 as shown, respectively.

In the modified form shown in Fig. 11, the side channel shapes 42 are disposed horizontally and may be joined to the bottom shape 105 19 directly, as illustrated.

In the modified form shown in Fig. 12, the channel shapes in the bottom of the vessel are disposed with their butt ends in staggered or broken relation with each other. This modified form is thus in sharp contrast to the preferred form above set forth, wherein the channel shapes in the bottom terminate on a given transverse line, preferably in 110 the bulkhead. Manifestly, instead of having the bulkhead plate 15 secured to a connection plate 14, on which the channels terminate, the bottom channels in this modified form are carried continuously through the bulkhead and made water-tight by a cast-steel or metal collar 46 around the flanges, 115 as shown in Fig. 13.

The mode of operation of a scow embodying my invention is as follows:

Since a scow is a vessel characterized by a particularly shallow depth as compared to its width of beam and length, together with other features hereinbefore set forth, and since the weight of said scow per lineal foot 130

longitudinally considered is much greater at the extreme end portions, it is manifest that the bottom members of a scow are normally put under compression, while the top or deck members thereof are normally put under tension. Respecting the increased weight at the ends, it is manifest that the extreme end portions of the vessel must have added thereto the weight of the end walls. Hence, there is created this greater weight longitudinally considered in the extreme ends of the vessel. It is further manifest that this condition of compression as respects the bottom, and tension as respects the top, is created by the manner of loading and unloading the scow. It is common practice to load or unload a scow as respects one end, thereby causing the same to be out of normal trim, even partially out of the water, so that it is unsupported as respects said end. Obviously, such disposition of the scow throws the bottom under compression and the top under tension. The scow may also be caused to trim by one end resting on the shore, while the other is in deep water. In short, said scow as an entity presents a veritable girder. In recognition of this situation, my invention provides a scow which takes advantage of this compression-tension situation, and provides for the spacing of the intermediate transverse members a plurality of times greater distance apart as compared to the disposition of said frames in similar vessels as heretofore constructed. Also, I reduce the number of longitudinal frame members in the form of keelsons and side stringers, so that the total weight of the scow is greatly reduced without loss of strength, since the flanges of the shell and deck channels are longitudinal stiffening in and of themselves.

The elimination of said material not only provides for a lighter scow and therefore of more shallow draft, so that the said scow is capable of use in shallow rivers or other shallow bodies of water, but it also accomplishes the very important feature of greatly reducing the cost of such a structure. Scows formed of wood gradually become water-soaked, so that it is customary to allow a high percentage for reduction in their carrying capacity. Thus, the carrying capacity of a scow varies with the age of the same, and is a matter that must be taken into consideration when the same is despatched to receive a load. A scow made of steel overcomes this objection. However, the objection to steel construction as heretofore designed is its great cost. So true is this that most scows at the present time are of wood construction. Hence, my invention overcomes the cost difficulty in one instance by eliminating the weight of the steel involved in its construction.

In the above it is pointed out that the bot-

tom and top of a scow by reason of loading or unloading may be placed under compression and tension, respectively. However, the construction of the scow must be such as to provide for the instances in which the load is disposed in the center only, so that it may be that said bottom and top may be under a tension and compression, respectively, i. e., just the reverse of the normal situation. The construction as herein set forth constituting my invention takes this into account, and provides a strength which will sustain this reversal of the normal condition of the top and bottom.

It is well recognized that a scow, by reason of its broad platform-like design, is peculiarly subjected to racking strains. In the steel scow, as heretofore constructed, these racking strains operate to shear off those rivets, or to work the same loose, which secure the keelsons to the transverse frame member, and in all other parts of the structure where the attachments are widely spaced, said attachments being necessarily widely spaced on account of the construction design. It is to be noted that according to present common practice design the attachments between the longitudinal frame member and the transverse frame are necessarily widely separated, as the attachments can only be made at the juncture point of the said frame members. This type of construction as stated is the more usual and accepted type, thus providing for the positioning of a longitudinal frame member, exceptionally heavy and strong, cross-sectionally considered, upon the transverse frame members, and the only connection between the two is a few rivets, the number of said rivets being necessarily few, owing to the fact that the area of the contact of the juncture does not permit a greater number. Thus, the real strength contributed by these members is measured by the strength of the attaching rivets. In short, the functioning of the maximum strength of the material in the frame members is not secured.

After some of the rivets are thus sheared or loosened, it eventually results in throwing an undue strain upon the rest of the frame members and also upon the hull. This condition or danger is overcome in the construction embodying my invention by reason of the fact that the entire structure is made practically integral. Particularly, the frame members, the transverse, the intermediate transverse and longitudinal, are practically made integral with the shell in the structure embodying my invention. The riveting of the lower members 16 of the longitudinal members to the shell, which are equivalent to the keelsons in the old type of vessel, is accomplished by riveting their lower edges between the flanges of adjacent channel shapes.

Moreover, heretofore, the practice has been to burn out notches in the transverse frame members to allow them to receive in said notches the flanges of the channel shapes.

5 This is objectionable, first, because it is expensive. The burning out of these notches consumes a great deal of time, and is accomplished ordinarily by acetylene burners and must be individually and manually accomplished. Second, serious objection obtains 10 to such notching of the transverse girder in that the strength of the same is thereby greatly reduced. In other words, a frame member of considerable weight is employed 15 without utilizing its strength. My invention overcomes this by constructing the transverse frame member of a channel unit 23 and attaching to said channel unit a plurality of clips 24. These clips therefore effect a close 20 pitched riveting entirely across the vessel as respects the lower edge of the lower unit or member 23 of the intermediate transverse frame. In fact, said lower member of the intermediate transverse frame is made practically integral with the shell bottom. Thus, 25 instead of having notches, which invite the locating of the fracture at said point, we have an intermediate transverse frame member on top of the flanges of channels 19, which member 30 has intact a top and bottom flange, the bottom flange providing a firm bearing on said channel flanges and consequently operating to prevent any fracturing of said member.

35 Furthermore, on the side of economy, my construction, as respects said clips 24, is such that it permits of the same being bull-riveted both as respects the shell bottom and also the unit 23 of said member. Thus, in all 40 these different ways, my invention provides for economical construction, so primarily essential in the steel scow type of vessel.

It is a well-recognized and well-known principle that a sudden change in the cross-sectional area of a girder results in a much 45 weaker girder than one which is uniform in its cross-sectional area throughout. That is, where the transverse frame member of fifteen-inches depth has a minimum of four-inch notches burned therein along its lower edge to provide for the receiving of the flanges of the bottom channel members, there is a sudden change in the cross-sectional area 50 equal to approximately twenty-five percent.

55 This change in the cross-sectional area occurs at frequent intervals throughout the length of the member. As noted, such a transverse member is much weaker than a transverse member of twelve inch depth that is not

60 notched. In short, the strength of such a member is a function of the uniformity of the cross-sectional area. Manifestly, the elimination of these notches, at the same time providing for the integral connection of the 65 intermediate transverse member with the

shell bottom provides for the employment of a much weaker, (consequently lighter in weight), transverse member by reason of the fact that its maximum efficiency is utilized. When a load is disposed on the scow, the 70 lower edge of the transverse member is thrown into great strains. Manifestly, the notching is a direct reduction of the strength of said girder along the precise lines or in that portion where the same should be 75 strongest, and in fact is a veritable starter for said fracture. To overcome any of these difficulties, much heavier transverse members must be employed, thereby adding to the weight, which is directly opposed to the efficient construction of a scow which must be of shallow draft and economical construction. However, while avoiding of the notches is 80 for these reasons preferable, notching may be employed where the use to which the scow is 85 to be put renders lightness of weight and strength a matter of indifference.

In all ship construction, it is a well recognized fact that the construction must provide a certain amount of elasticity, owing to the fact that ships are subjected to a multiplicity of strains due to varying support of the water in rough weather, and particularly is this true in a scow due to lack of uniformity of loading. An invariable rule adhered to is the positive avoidance of too great rigidity. In a scow construction, being of the broad platform-like design, the importance of the necessary degree of elasticity is 90 of double significance. The racking strains, to which such a structure is peculiarly subjected, most emphatically call for a relatively high degree of elasticity compared with the ordinary ship construction. This 95 requisite condition therefore calls for a transverse frame member of minimum material to supply the necessary degree of strength. My construction of securing by means of clips 24 the lower unit 23 of the intermediate transverse frame member to the shell bottom, 100 making the same practically integral therewith, provides for utilizing the maximum efficiency of the strength of said lower unit, and, therefore, I make possible the employment of a unit having a minimum of material therein, which in turn provides for the 105 maximum elasticity in such a member.

110 It is manifest throughout the above that applicant has discovered and solved through his invention the problem of providing a minimum of material to effect the requisite strength in a scow, thereby effecting an efficient type of such vessel as well as one of greatest economical construction.

115 While said elasticity is a positive requisite in a structure of the type of vessel under consideration, nevertheless on the other hand it is necessary to provide sufficient strength to maintain said elasticity within predetermined limits. Therefore, I preferably dis- 120 125 130

pose the channel shapes composing the side shell vertically. Manifestly, this vertical disposition of the side channel shapes effects a much stiffer (vertically considered) side wall than is inherent in a side wall composed of channel shapes, where the said shapes run longitudinally. Furthermore, a condition which must be satisfied, as respects the side wall, is that the same must possess sufficient strength to resist laterally directed forces, such as the pressure created by coming in collision broadside on with docks and other vessels, and also the blow consequent upon a heavy wave breaking against her side. I provide for this necessary strength, in conjunction with my relatively weak transverse and intermediate transverse members, by disposing the side shell channel shapes vertically. Where the said side shell channel shapes are disposed longitudinally, they are only strongly supported at intervals equal to the distance between the bulkheads. In short, the said side channels constitute a girder supported at said intervals. My intermediate transverse members, intermediate said bulkheads, of proportions employed in my invention, would afford little or no support against the pressures which I have above indicated. In this particular, we are dealing with a local force and an obvious condition which must be provided for, and particularly in the case of the side shell. In the scow embodying my invention, in the preferred form of having the channels vertically disposed, I provide relatively short spans from the deck to the bottom, providing for a side shell of requisite strength, and, be it noted, without in any wise interfering with the necessary elasticity as respects the bottom units as heretofore pointed out.

As respects the frame members, longitudinal transverse and intermediate transverse the structure embodying my invention eliminates material and provides for the employment of relatively very weak members to provide for a strength generally throughout the structure, and this provision, in conjunction with the preferably vertically disposed channel shapes in the side shell, takes care of the condition of local strength.

The above has reference to a scow structure embodying my invention generally, in contrast to the following which pertains to a definite form of my structure herein styled "panel" construction.

In the employment of channel shapes in the construction of vessels, as heretofore designed or suggested, the joints of the channels are carefully disposed in "staggered" or "broken" relation, or as technically known in the art as "a shift of butts". In this definite panel form of construction, the structure embodying my invention proceeds in direct opposition to said general practice by

terminating the joints along a given transverse line, thus dividing the shell into sections, or as herein termed "panels". The advantages accruing are many: First, the economy incident thereto is to be noted. The channel shapes 19 constituting the bottom are ordered from the mill, cut to desired lengths. These shapes may be installed in one of two ways as follows:

After constructing the bulkheads or transverse frame member by securing to the bulkhead plate 15 the boundary bar 13, and securing to said boundary bar the connection plate 14 and disposing these on the cribbing on the building ways, thereupon the bottom unit 16 of the longitudinal frame member or members is put into position or obviously a channel member as in the case of the intermediate transverse member could be employed as a transverse frame member. This bottom longitudinal frame unit 16 consists of the vertically disposed plate 34 (Fig. 5) with the stiffening angle or flange 35 on its upper edge. Thereupon, the channel shapes 19 are put in position on either side of plate 34 with their ends resting on the connection plate 14, to which they are bull-riveted. These channel shapes 19 are then bull-riveted together through the plate 34 along their respective flanges. Then the remaining channel shapes, which go to make up the remainder of the shell bottom, are placed in position, preferably from the center line of the vessel outwardly, and are bull-riveted one by one along their respective flanges, and to the connection plate 14. The clips 24 are bull-riveted in place, one by one, as the said channels are placed in position.

Thus, there is formed a panel 36 in the shell bottom, extending from bulkhead to bulkhead or transverse to transverse frame member wholly independent of any of the remainder of the vessel fore and aft. This panel, as respects its width, obviously may be considered as extending from the center line to the side shell, or from the center line to the next longitudinal bottom unit, if there are said longitudinal units.

A second way in which the said bottom channels may be put in place is as follows: The channel shapes may be placed side by side in the fabricating department, and bull-riveted along their flanges with the necessary clips 24, so that the panel complete is thus constructed, whether the same extends from the center line to the next longitudinal member, or whether the same extends from the center line to the side shell. This panel thus made is then taken and dropped in position between the bulkheads or transverse frame member and the ends riveted to the connection plates 14. In placing the panels according to this second way, the vertical bulkhead or transverse frame plates 15 would not be put in position until the shell

bottom was finished from one end of the scow to the other. On a given panel, the connection plates 14 with the boundary bar 13 riveted thereto would be bull-riveted at 5 each end of said given panel. The next adjoining panel would not be provided with a connection plate 14 as respects one end. This end would be gun riveted to the connection plate of the said first panel. This 10 illustrates one of many modified ways in which the said panels may be fabricated as a unit and installed.

The fabricating of the panel and the installing of the same as a unit as just set 15 forth may be advantageous in those shipyards where the said fabricating shop is equipped with hoisting and conveying machinery for handling complete panels.

A similar procedure may be adopted in 20 connection with the construction of the side shell, namely, the two channel shapes joining the bulkheads or the transverse frames or the intermediate transverse frames may be riveted to the respective bulkheads or 25 transverse frames or intermediate transverse frame members, and the space left between may be filled in channel by channel, or the panel as a complete unit fabricated and riveted in the shop and placed in position between 30 said members.

Manifestly, this panel construction and the connection plates 14 provide for utilizing 35 the channel shapes without correcting any discrepancy that may occur as to their length. The said shapes may be employed as received from the mill. Ordinarily, there will be a discrepancy between the ordered length and the delivered length. However, since the ends of the said channels are in 40 spaced relation to the bulkhead or transverse frame member, allowance is made for this discrepancy in the width of the connection plate 14. This construction obviously provides for the punching of rivet holes in the 45 flanges and webs of the channel plates from a universal template applicable to the whole of the flat portion of the bottom. A separate universal template likewise applies to the side shell channels.

50 This making applicable the use of the universal template effects a great economy as respects the labor cost. These panels are preferably of a uniform length throughout the ship, and thus all the channels making up 55 panels are of the same ordered length, thereby making the channels universally interchangeable throughout the bottom of the ship, and also making the channels in the side shell universally interchangeable. This 60 avoids the necessity in constructing, for example, the bottom panels of channel shapes of a particular length, and also this eliminates the necessity of sorting and handling the material upon its receipt from the mill.

65 In shipbuilding, seventy-five cents of every riveting.

one dollar spent on steel construction labor goes for unskilled labor, and of this seventy-five cents at least fifty percent is spent for handling and sorting the material, owing to the great variety in dimensions of said materials. 70

This panel construction is made possible by reason of the fact that in the scow construction the bottom and top are respectively under compression and tension strains, as 75 hereinbefore set forth.

The next part of the hull to be put in position would normally be the lattice members 29, which are secured at their ends and center to brackets 30, 37 and 38. Next, the 80 upper unit 28 of the longitudinal member is installed, and, thereupon, the beams 26 of the intermediate transverse members, the same being preferably intercostal. Upon these beams, the deck channels 31 are placed and 85 bull-riveted, the same being preferably disposed with their flanges upwardly directed and being bull-riveted along their flanges as well as to the beams 26. The channel shape 39, having either one flange cut off or both 90 flanges left intact, abutting on the side shell is carried sufficiently over the side shell to take the gunwale angle 40. The gunwale angle 40 and the fender angles 41 are preferably continuous from one end of the vessel 95 to the other.

As is generally known in the rolling of shapes of considerable sectional area, there is a marked difference in the width, due to the variation in temperature of the rolls and 100 the material from which the shapes are being rolled. While this variation is not serious in the smaller sections, it entails considerable cost and work when any two sections of different width are to abut or join each other 105 endwise. My panel construction overcomes this objection, inasmuch as no two channels are caused to abut or be joined endwise. My panel construction provides for using 110 channels of different width. To illustrate this, it is evident that my panel construction allows for the construction of channels in one panel of a different width than those in the adjoining panel. This is of the utmost importance, and has hitherto been a most 115 serious objection to the employing of channel shapes in hull construction. It is manifest that the variations in width would entail the introduction of metal packing between the flanges of one channel and another, 120 in order to bring the flanges in line at the butts of abutting channel shapes, whose width varies. A vacancy would be left laterally, equivalent to the discrepancy in 125 width of the two abutting channels. This necessitates the introduction of either parallel or tapered liners, a very objectionable feature in shipbuilding, not only by reason of its cost, but the introduction of three ply 130

Obviously, changes may be made in the forms, dimensions and arrangement of the parts of my invention, without departing from the principle thereof, the above setting forth only preferred forms of embodiment. In the modified form shown in Figs. 12 and 13, the bottom channel members 43 have broken or staggered joints 44 and 45, with metal collars 46 in conjunction with the bulk-head 12. This represents the more usual form of disposing the bottom channel members, but constructing the balance of the hull as provided for in the preferred form permits of the resulting economies as hereinabove set forth. The spacing of the intermediate transverse frames being a multiple times further apart provides for the construction of a scow much cheaper than is common at present.

20 I claim:—

1. A steel scow, barge or like vessel embodying a hull, square in vertical cross section at all transverse planes, said hull being composed of channel shapes, the flanges of which are secured together, said shapes in the bottom being of sectional formation the sections having their ends in spaced relation longitudinally and terminating in given lines transverse to the ship; and a connecting plate disposed transversely of the hull in a plane parallel to the hull to which the end portions of said channel shapes are secured, whereby drainage of all liquids in said bottom is provided, and difficulties due to varying lengths and widths of the channel shapes are obviated.

2. A steel scow, barge or like vessel embodying a hull composed of channel shapes having flanges secured together, said shapes in the bottom being of sectional formation the sections having their ends in spaced relation longitudinally and terminating in given lines transverse to the ship; a connecting plate disposed transversely of the hull in a plane parallel to the hull to which the end portions of said channel shapes are secured; and transverse frame members secured to said plate between said end portions.

3. A steel scow, barge or like vessel embodying a hull composed of channel shapes having flanges secured together, said shapes in the bottom being of sectional formation the sections having their ends in spaced relation longitudinally and terminating in given lines transverse to the ship; a connecting plate disposed transversely of the hull in a plane parallel to the hull to which the end portions of said channel shapes are secured; transverse frame members secured to said plate between said end portions and longitudinal frame members secured substantially throughout their length to the channel shapes.

4. In the method of constructing a steel

scow, barge or like vessel hull of steel channel shapes of varying length and width, said hull having longitudinal and transverse truss members, the steps of building into panels a plurality of said channel shapes for the bottom and sides; inserting said side and bottom panels in spaced relation, as respects their vertical and horizontal planes respectively, to each other; inserting said panels in spaced relation as respects their ends between said truss members; securing the end portions of said panels together by means of a connector member; and joining said sides and bottom panels by means of a bilge plate extending throughout the length of and up the rakes to the deck of the scow.

5. In the method of constructing a steel scow, barge or like vessel hull of steel channel shapes of varying length, said hull having longitudinal and transverse truss members, the steps of building into panels a plurality of said channel shapes for the bottom and sides, inserting said panels in spaced relation as respects their ends between said truss members, and securing the end portions of said panels together by means of a connector member.

6. In the method of constructing a steel scow or like vessel hull, the steps of building the bottom in panels or sections of channel shapes, which panels are of a length to extend from transverse frame member to transverse frame member, of building the side panels of channel shapes, said panels being of a length to extend from transverse frame member to transverse frame member, and the channel shapes themselves being disposed vertically, and transverse frames having their lateral edges secured between the flanges of the channel shapes in the sides, and their lower edges secured to the bottom channel shapes.

7. The method of constructing a steel scow or like vessel constructed of channel shapes, comprising the steps of making a transverse member formed of a boundary bar with a transverse shell connection riveted thereupon; of placing said transverse member on cribbing prepared on the building ways; of constructing the bottom member of the longitudinal girder and placing same in position between transverse members on building ways; of forming a bottom panel of channel shapes previously marked and punched from a universal template, said shapes being of lengths as received from the mills, by riveting said channel shapes together along their flanges, whereby is formed a panel of desired width, having the ends of said channel shapes terminate along a given transverse line; of forming a side panel of channel plates previously marked and punched from a universal template, said shapes being of lengths as received from the

5 mills, by riveting said channel shapes together along their flanges, whereby is formed a panel of desired width extending in length from one transverse member to the other; of securing in place the intermediate transverse frame members as respects bottom and sides, said intermediate transverse members being spaced a plurality of times further apart than has heretofore been customary in

the same class of vessel transversely framed; 10 of erecting the web member of the longitudinal girder; of erecting the beams of the transverse frame member; and of marking, punching, placing in position and riveting the deck channels. 15

In witness whereof, I hereunto subscribe my name this 12th day of December, 1924.

ROBERT ELWOOD ELLIS.
